UNITED STATES PATENT OFFICE

2,033,496

SHOE MACHINE

Laurence E. Topham, Wenham, Mass., assignor to
United Shoe Machinery Corporation, Paterson,
N. J., a corporation of New Jersey

Application July 3, 1934, Serial No. 733,588

27 Claims. (Cl. 12—17)

The present invention relates primarily to improvements in shoe machines of the automatic type such, for example, as disclosed in U. S. patents to the present inventor Nos. 1,616,710 and 1,753,452, in which the shoe and the means for operating on the shoe are moved relatively to transfer the point of operation along the shoe with a linear feeding movement and the relative positions of the shoe and the operating means are simultaneously changed in other respects so that the shoe may be presented properly to the operating means as the point of operation is transferred about the shoe.

In machines of the type particularly referred to, the shoe is supported on a movable jack and the operating means are provided with feeding devices acting directly on the shoe. To present the shoe properly to the operating means as the shoe is fed, the position of the jack is changed progressively by a pattern cam shaft driven one complete rotation for each shoe operated upon. In order that the cam shaft may be rotated at the proper speed relative to the speed at which the shoe is fed, the cam shaft is driven by the operating means through changeable speed gearing.

In an automatic shoe machine, changes of relative speed between the operating means and the pattern cam shaft are necessary to meet with two requirements; namely, change in shoe size and change in rate of feed. With changes in either shoe size or rate of feed, the cam shaft must be turned at a higher or lower speed to maintain the proper time relation throughout an operation on the shoe. In the case of a shoe sewing machine, and particularly an outsole stitcher, this time relation is dependent principally on the number of stitches required to sew the complete outsole seam. With a small shoe, the seam may be completed quickly, with a small number of stitches, while with a large shoe, a much greater number of stitches are required with a corresponding increase in the time required to complete the seam. In shoe sewing machines the length of each stitch may be changed by regulating the feeding movement of the sewing devices. With a short feeding movement, a much larger number of stitches and a longer sewing operation are required for a given shoe than with a longer feeding movement. For these reasons when an extreme feeding movement has been required on a shoe of extreme size, considerable difficulty has heretofore been encountered in providing accurate adjustment of the speed ratio between the operating means and

the cam shaft and particularly so when automatically actuated adjustments are provided to compensate for such changes.

If mechanism is provided for automatically changing the speed ratio of mechanical gearing throughout the full required range, while the sewing machine is running, to bring the cam shaft and the shoe into proper time relation whenever either is displaced from the other, periodic fluctuations in the amount of displacement may occur due to the great range of the changes required. In certain automatic machines, the changes in speed are produced in abrupt steps which, when extreme changes are required, cause irregularities in the work or an undesirable series of shocks in the gearing of the machine. One reason for such difficulties is that previous attempts to automatically correct the speeds of moving parts of these machines have been based on a principle requiring a predetermined displacement from proper time relation of the parts before a correctional impulse is imparted. With such an arrangement, the displacement is constantly increasing or decreasing between relatively wide limits, and any tendency for the parts to seek a natural oscillatory period of relative movement or to hunt, is accentuated and this tendency increases during continued operation of the machine.

An object of the present invention is to provide a novel and improved automatic speed control for shoe machines of the automatic type having shoe position changing mechanisms to insure that the positioning movements of the shoe will at all times be automatically made to correspond with the feeding movements imparted by the shoe feeding means throughout the full required range of relative speed changes without imparting undesirable shocks to the drive gearing or tending to produce independent periodic movements of the machine parts.

A further object of the invention is to provide a novel and improved system for automatically regulating the relative movements of two separately actuated machine parts, such as the feeding means and the pattern cam shaft of an automatic shoe machine which will operate more evenly and more quietly than previous speed control systems heretofore employed.

With these objects in view, the present invention contemplates the provision in an automatic shoe machine of the type referred to having a shoe supporting jack, operating means including shoe feeding devices, mechanisms for otherwise changing the relative positions of the jack and

the operating means, a control member operating when the feeding movement of the shoe is out of time with the other positioning movements, of regulating means for arbitrarily actuating the 5 control member during successive feeding movements of the shoe for a length of time varying with the extent by which the positioning movements and the shoe feeding movements are out of time.

10 While the features of the invention are illustrated and are hereinafter described as being applied to an automatic shoe sewing machine of the type above referred to, certain features are considered of broader scope and may be employed 15 to advantage in other types of machines where two actuated parts are to be maintained closely in predetermined relative positions even though driven by separate driving means. When so driven, connections of some sort are required between the parts for affecting the control member to return the parts to their predetermined proper relation. By providing in addition a regulating 20 means for the control member which causes the control member to act during successive movements of the parts without regard to any fixed amount of displacement, or in one form of the invention, during regular time periods with alternate intervals of inactivity, the tendency of the parts to seek an oscillatory or hunting period of 25 relative movement in which first one is too fast and then the other, is eliminated. It is therefore desirable to provide a driver for the regulating means operating at sufficiently high a speed that the changes in speed of one part during each 30 correctional period or impulse of the control member will have substantially no appreciable effect on the operation of the machine as a whole.

The displacement of the parts may, according 40 to the preferred form of the invention, be arranged to affect the control member by applying a force tending to actuate the control member. The regulating means then acts to counteract the force of the connections and causes the control member to be actuated during such times only 45 as will most effectively relieve the out of time conditions. The driver for the regulating means is preferably rotated uniformly so that the intervals in which the control member is held inactive bear a relationship to each actuated time 50 corresponding to the ratio of the counteracting effect of the regulating means and the actuating force.

55 As illustrated, the control member actuates electrical contacts, one of which causes return of the actuated parts to proper positions when one of the parts is too fast and another of which causes return of the actuated parts when the other part is too fast. The regulating means is in the form of a spring connected between a periodically vibrating member and the control member to resist actuation thereof at arbitrary intervals.

60 Another feature of the invention relates to the use, in an automatic shoe machine having means for operating on a shoe, shoe feeding means, a shoe supporting jack, a pattern cam shaft for causing movements of the shoe other than feeding movements to present the shoe properly to the operating means as the shoe is fed, a driver 65 for the operating and feeding means, of separate driving means for the cam shaft and a suitable control member for changing the speed of the separate driving means relatively to the operating means. As a separate driving means for the cam shaft, a variable speed electric motor

may be employed, controlled directly by the control member so that the mechanical limitations of the usual variable speed gearing are avoided.

The features of the invention above referred to, and other novel constructions, combinations and arrangements of parts hereinafter described and claimed will be readily understood by those skilled in the art from the following description taken in connection with the accompanying drawings which illustrate one specific embodiment of the invention.

In the drawings, Fig. 1 is a view in front elevation of the principal parts of a machine embodying the features of the invention; Fig. 2 is a plan view of the base of the machine; Fig. 3 is a view in side elevation looking from the right and showing portions of the driving mechanism; Fig. 4 is a detail view on an enlarged scale of certain connected parts of the machine broken away and shown in proper composite relation; Fig. 5 is a sectional view similarly broken away, of connected parts of the machine taken along the line 5—5 of Fig. 2; Fig. 6 is a similar sectional view of portions of the control connections taken along the line 6—6 of Fig. 2; Fig. 7 is a plan view on a still further enlarged scale of a part of the control mechanism; Fig. 8 is a detail view, shown partly in section, of another part of the synchronizing mechanism; Fig. 9 is a view in elevation and partly in section as viewed along the line 9—9 of Fig. 7; Fig. 10 is another sectional view of the same mechanism as viewed along the line 10—10 of Fig. 7; Fig. 11 is a sectional view taken along the line 11—11 of Fig. 5; Fig. 12 is a sectional view of the mechanism along the line 12—12 of Fig. 5; Fig. 13 is a sectional plan view of the connections shown in Fig. 6 as viewed along the line 13—13; Fig. 14 is a sectional view of parts of the control mechanism taken along the line 14—14 of Fig. 8; Fig. 15 is another sectional plan view along the line 15—15 of Fig. 6; Fig. 16 is a sectional detail view of certain of the parts of Fig. 15 shown in elevation; and Fig. 17 is a schematic diagram of the electrical connections in the machine.

The machine illustrated in the drawings is an automatic outsole shoe sewing machine having a main base 2 arranged to carry frames 4 and 6 for the sewing and power drive mechanisms, respectively. The power drive frame 6 supports a frame 8 carrying a starting mechanism and a driving motor 10 above it. The motor 10 drives a vertical shaft 12 to operate the constantly rotating driver, indicated at 14. The driver is fast on a vertical shaft 16 and is formed at its lower portion with a clutching surface to engage a similarly shaped surface on a driven clutch member 18 yieldingly urged towards the driver 14. The driven clutch member is held from engagement with the rotating driver by a lock bolt 20, (see Fig. 3) and the lock bolt is released to start the machine by the mechanism contained in the frame 8 which is controlled by a handle 22 projecting from said frame. The driven clutch member 18 is connected by helical gears 24 to a main sewing shaft 26 for actuating lock stitch sewing mechanism comprising a shuttle 28, a presser foot 30, a feed slide 32 and other stitch forming and work feeding members which are substantially the same as those illustrated and described in the application for U. S. patent of O. R. Haas, Serial No. 600,016, filed March 19, 1932. At the end of the sewing operation or in case of a mis-stitch, the driven clutch member 18 is disengaged from the main driver 14, as will be described herein-

after, to bring the sewing mechanism to rest in such a position as to permit the shoe, indicated at 34, to be readily removed.

The work feeding devices of the machine comprise the feed slide 32 together with the stitch forming devices which are supported thereon. These work feeding devices operate to impart a continuous linear feeding movement to the shoe to transfer the point of operation of the stitch forming devices along the marginal portions of the outsole. The length of each stitch by the stitch forming devices may be changed by properly manipulating a feed regulating device 35, as described more particularly in the Haas application referred to.

To support the shoe, a jack 36 is provided, suitably mounted within the main frame 2 of the machine to permit the jack to be given the proper tipping and turning movements as the shoe is fed by the feeding devices. These movements are imparted to the jack by mechanism comprising cams on a pattern cam shaft 38, followers 40 actuated by the cams and suitable connections between the cam followers and the jack.

The connections between the cam followers 40 and the jack include adjustable means for actuating a feed control arm 42 at the same rate of speed as that at which the shoe is fed. The control arm connections comprise a bell crank 44 (Figs. 2 and 3) on which is mounted one of the cam followers 40. The feed arm 42 is pivoted to the main frame 2 of the machine at 46 and is connected to the cam operated lever 44 by links 48 and 50. The link 48 is pivotally connected to the feed arm 42 and to one end of the link 50 by a pivot 52, the other end of the link 50 being pivotally connected to an arm of the bell crank 44. The free end of the feed arm 42 is connected to the toe supporting portion of the jack 36 by a link 53.

To permit movement of the feed arm 42 to be changed for different sizes of shoes without changing the shape of the cam on the pattern cam shaft which actuates the bell crank 44, the pivot 52 is connected by a link 56 to an arm 58 mounted on a fixed shaft 60, so that before sewing is begun, the arm 42 may be shifted about its pivot 46, causing the arm 58 to rotate about the shaft 60.

Before the machine is started in operation, the position of the feed arm 42 is shifted as the shoe is being moved to proper position relative to the stitch forming devices. The arm 58 is locked in position during sewing so that the arm 42 may not move thereafter except as actuated from the bell crank 44. To lock the arm 58, a clamping device 62 is provided which is actuated by a link 64 to grip a rod 66 pivotally connected at one end to the end of the arm 58. These and other connections between the pattern cam shaft and the jack are similar and operate in substantially the same manner as in the machine of applicant's prior patents above noted to which reference may be had for a more exact and complete description.

The machine is brought to rest by driving and stopping mechanisms comprising the lock bolt 20 (see Fig. 3) mounted in a carrier 68 and arranged to engage a cam slot 70 in a sleeve portion of the driven clutch member 18. The carrier 68 is in the form of a bell-crank, one arm of which cooperates with a spring pressed latch 72 to hold the carrier in fixed position when the machine is stopped. To operate the driving and stopping mechanism upon the completion of a seam, shaft

38 carries a cam block 74 (see Fig. 4) arranged to oscillate a lever 76 fulcrumed on a vertical shaft 78 and through connections including a link 80 pivotally connected to lever 76, the latch 72 is permitted to yieldingly engage the carrier 68, thus causing the lock bolt to be held stationary and the driven clutch member to be disengaged from the main driver 14, as more fully explained in the Haas application.

The pattern cam shaft in the machines described in the inventor's patents and in the Haas application is rotated by a driving gear train between the driven clutch member 18 and the cam shaft 38. When the cam shaft is not in proper position, during sewing, relative to the feeding position of the shoe, the rotary speed of the cam shaft is increased or decreased by abruptly changing the effective speed ratio of driving gears between the clutch member 18 and the pattern cam shaft. If the range of speed ratios is made sufficiently great when using an abrupt shift to automatically regulate the speed, the steps between relative speed changes may be so great as to cause heavy shocks in the driving gear train and other undesirable effects on the machine. The range of possible speed change, therefore, where the speed ratio is abruptly changed is not sufficient to permit sewing of all shoe sizes without supplementary manual adjustments or without changing cams on the pattern cam shaft. Also, if the changes of relative speeds between the cam shaft 38 and the clutch member 18 are abrupt and of great difference, improper operation of the sewing machine may take place each time the speed ratio is changed.

To control the machines of the patents referred to when the shoe, during sewing, becomes displaced in the direction of feed relatively to the proper position of the cam shaft, a member is actuated to return the positions of the shoe and the cam shaft to their proper relations. The control member is arranged to be actuated by a relative movement between the feed control arm 42 and the link 53 which is connected to the jack. The control member is actuated only when a predetermined minimum displacement occurs, and due to unavoidable lost motion and time lag in response to actuation of the control member, considerable displacement or fluctuation in relative speeds may occur before the parts are returned to their proper relations.

In the machine embodying the present invention the control member, indicated at 82, (see Fig. 7) is actuated irrespective of extent of relative displacement between the feeding position of the shoe and the position of the cam shaft. The control member, as will be described in more detail hereinafter, is operated upon by a regulating device at recurring intervals to cause it to be actuated and to change the relative speeds of the controlled parts only during such short periods of time that extremely small amounts of relative displacement or change in relative speeds of the controlled parts will occur in any one period.

To cause the control member 82 to provide effective control when actuated during short periods of time, it is held alternately in actuated and inactive positions during each period, and the time when the control member is actuated in each period bears a relation to the inactive time in each period corresponding to the extent by which the feeding position of the shoe is displaced from the proper relative position of the cam shaft during the feeding movement of that period. Relative displacement of the shoe in the direction

of feed from the position of the cam shaft causes either of two springs 84 to apply force in one direction to the control member 82 proportional in intensity to the extent of the displacement. The 5 displacement force of the springs 84 is, in part, resisted by a periodically varying force in the other direction imparted by a spring 86 in the regulating device, the resultant of the spring forces caused by displacement and by the regulating device acting to cause a periodic correcting impulse to be imparted to the cam shaft for a length of time corresponding to the intensity of the force produced by relative displacement in feeding position of the shoe during each period.

15 To tension springs 84 whenever the feeding position of the shoe is relatively displaced from the position of the cam shaft, the link 53 is pivotally connected to one arm of a horizontally arranged lever 88 secured to the lower end of a 20 short vertical shaft 90 rotatable in a bearing formed at the end of the control arm 42. To the upper end of the shaft 90 is fixed a lever 92 acting between two set screws 94 and 96 carried by a pair of L-shaped levers 98 and 100, respectively, to which the springs 84 are connected. The levers 98 and 100 are fulcrumed on vertical pivots 102 and 104, supported at their upper ends in a block 106 and at their lower ends in the control arm 42. The L-shaped levers 98 and 100 25 pass through spaced slots in the block 106 and the block is rigidly secured to the feed arm by screws 108. When relative movement occurs between the feed arm 42 and the link 53, the lever 88 rocks the shaft 90 in its bearing and causes the 30 lever 92 to engage either set screw 94 or 96, rocking the corresponding L-shaped lever and tensioning the corresponding spring 84 proportionately to the displacement.

To resist the force of the springs 84, the 35 control member 82 acts itself as a lever having a stud screw 110 passing loosely through its central portion and into threaded engagement with an arm 112 pivotally mounted at 114 to the feed control arm, and the control member 82 is urged 40 towards inactive position by the regulating spring 86 connected between the fulcrum screw 110 of the control member and an arm 116 rotatably mounted on a stud 118. The hub of the arm 116 extends upwardly and is surrounded by the 45 hub of an arm 120 clamped in fixed angular relation to the arm 116 by a clamping screw 122. The arm 120 is vibrated continuously as the shoe is being operated upon, by a rotary cam 124 secured to the upper end of a vertical shaft 126. The free end of the arm 120 is provided 50 with a follower 128 engaging the cam 124, and the cam is of such shape that during its rotation the tensioning stress applied to prevent rocking the control member increases uniformly until a 55 predetermined maximum is reached. Thereafter, the tension of spring 86 is reduced to a minimum and again uniformly increased. The increase and decrease of tension on the spring 86 takes place 60 during successive feeding movements of the shoe periodically and at such a rate that each 65 correctional impulse will produce but an extremely slight relative change of speed between the feeding movement of the shoe and the speed of the cam shaft, so as not to interfere with the operation 70 of the sewing devices. With a sewing machine operating at 560 or 600 R. P. M. periodic increases of spring tension at the rate of two or three a second has been found effective.

The control member acts to change the 75 relative speeds of the sewing machine and the pat-

tern cam shaft 38 by disengaging electrical contacts 130 and 132 on the control lever 82 from stationary contacts 134 and 136. Electrical circuits connected to the contacts are so arranged that when both movable contacts or neither 5 engage their respective stationary contacts, no change in speed of the cam shaft will take place, so that angular rocking movement of the control member is necessary to actuate it. When the control member 82 is actuated by rocking it about 10 its fulcrum 110, one of the movable contacts is periodically disengaged from the corresponding stationary contact during such a time in each period as the force of spring 86 is less than that of the tensioned spring 84. When this occurs, 15 the speed of the cam shaft is changed. The force of the tensioned spring 84 being a measure of the displacement, the times in which the control member is held actuated and inactive in each period will bear a relation corresponding to the 20 relative displacement of the parts controlled.

The relative change of speed is effected by controlling the speed of a three-phase induction motor, indicated at 138 mounted at the side of the machine. This motor is separate from the 25 main driver 14 of the machine and acts only to change the position of the cam shaft. As illustrated diagrammatically in Figure 17, the feeding movement of the shoe is indicated as being too fast with relation to the speed of the cam 30 shaft 38 and the lever 92 is shown engaging set screw 94 to rock lever 98 and apply a tension on one only of the springs 84, disengaging contact 132 from stationary contact 136. This movement opens the circuit to a control magnet 140 and 35 the armature 142 thereof is released, permitting contacts 144 to become engaged. Engaging the contacts 144 causes the rotor of the motor 138 to revolve in the direction of the arrow. A similar magnet 146 having an armature 148 controlling 40 contacts 150 is provided for causing the motor to rotate in the opposite direction.

The motor is supplied with current from three-phase mains 152 which also energize a transformer 154 grounded at 156 for supplying energy 45 to the magnets 140 and 146. To prevent the contacts which control rotation of the motor in opposite directions from becoming engaged at the same time, two centrally pivoted insulated levers 50 158 are each arranged with their ends engaging one movable contact 144 and one movable contact 150.

The pattern cam shaft 38 is rotated through a system of gearing including a differential between the gear 24 on the driven clutch member 55 18 and a gear 159 on the pattern cam shaft 38. The gear train comprises a gear 160 meshing with the gear 24, a shaft 162 to the upper end of which the gear 160 is secured, a pinion 164 at the lower end of the shaft meshing with a 60 set of idlers 166 rotatable on studs 168, a spider 170 carrying studs 168 rotatable on the shaft 162, a gear 172 formed at the upper end of a hollow shaft 173 connected through a tongue and slot connection with the hub of the spider 65 170, a gear 174 meshing with the gear 172, a gear 176 rotatable with the gear 174 and arranged to mesh with a gear 178, a pinion 180 secured to the gear 178 to mesh with a gear 182, a series of gears 184 fixed to a shaft 186 to which the 70 gear 182 is connected meshing with the gear 159 at the upper end of the cam shaft 38.

The correcting impulses produced by the control member 82 are imparted to the cam shaft 38 by the motor 138 acting through the system 75

of differential gears comprising the pinion 164, idlers 166, a hollow gear member 188 rotatable about the lower end of the shaft 162 and also formed with a bearing on the hub of the spider 170. The hollow gear is formed with internal gear teeth 190 which engage the idlers 166 and with external bevel gear teeth 192 which mesh with a bevel gear 194. The gear 194 is secured to the inner end of a shaft 196 the outer end of which carries a gear 198. The gear 198 is driven by means of a gear 200 on the motor shaft engaging the gear 198.

The vertical shaft 162, for convenience in assembling the machine, is formed in two parts which are connected together by means of a disconnectible clutch, best shown in Figs. 5 and 12. The clutch consists of a clutch block 202 secured to the upper end of the lower portion of shaft 162 and a block 204 connected with the upper portion of the shaft 162. The block 204 is slotted to slidingly receive a tongue 206 formed on a clutch member 208 yielding forced against the block 202 by means of springs 210. The lower portion of the clutch member 208 carries a pair of vertical pins 212 engaging diametrically opposite holes in the upper part of the block 202 so as to provide positive driving means in both directions between the portions of the shaft 162.

To support the shafts 162 and 196 in proper relation with the gears 192 and 194 in engagement, the shaft 196 rotates in bearings formed at the ends of a horizontal sleeve 214, one end of which is secured to the main frame 2 of the machine and the other end of which is engaged by an angular bracket 216 having a vertical bearing bushing 218 surrounding the hub of the spider 170. The bearing 218 is formed with a flange at its lower end to engage the upper surface of the hollow gear 188, separable parts of which are secured together by means of bolts 220. The spider 170 bears against the upper surface of the pinion 164 which is secured to the shaft 162. The hollow gear 188, in turn, rests on the spider and the bearing 218 being supported by the ring gear, acts to prevent downward movement of the angular bracket 216.

The ratio of the driving gears between the driven clutch member 18 and the pattern cam shaft 38 is such as to produce a complete rotation of the cam shaft when a shoe of the average size, that is, approximately a number 7, is being sewed with a stitch of the average length, or approximately eight stitches to the inch. If the position of the feed adjustment 35 or the size of a shoe is changed, the ratio of the driving gears between the clutch member 18 and the pattern cam shaft is no longer suitable to keep the rotation of the cam shaft and the feeding movement of the shoe in the proper time relation.

As soon as a relative change in feed of the shoe effects the control member 82, the motor 138 will be started in operation to correct the position of the cam shaft accordingly. The oscillations of the arm 116 in the regulating device affecting the control member 82, act at such a rapid rate that before the motor 138 has had a chance to come to rest, from one correctional impulse, another is imparted to it so that it continues to rotate slowly at a speed determined by the time during which the control member 82 is held in actuated position with one of the contacts 130 or 132 held separated from the corresponding contact 134 or 136.

To drive the regulator shaft 126 which is mounted in a suitable bearing in the feed control arm 42, the lower end of the shaft carries a gear

222 (Figs. 7, 8 and 14) meshing with a worm 224 fixed to a horizontal shaft 226 extending in parallel relation to the feed control arm 42. The forward end of the shaft 226 is rotatably supported in a bearing block 228 pivotally connected by a screw 230 to an arm 232 rotatable about a stud screw 234 threaded into a boss 236 projecting downwardly from the under-surface of the feed arm 42. The rearward end of the shaft 226 is rotatably supported in a bearing block 238 (see Figs. 9 and 15) pivotally mounted between the forked ends of a bell crank lever 240 having a fulcrum 242 at the inner end of the feed control arm. The shaft 226 is rotated by a constant speed motor 244 mounted on the feed arm and having a driving pinion 246 meshing with a gear 248 secured to the inner end of shaft 226.

In order to prevent rotation of the correcting motor 138 when the machine is brought to rest and the size adjustable link connections between the cam shaft and the feed control arm are unlocked at the end of the operation on a shoe, means are provided for locking the lever 88 and the control member 82 against rocking movement, and the contacts 134 and 136 are short circuited so that regardless of the position of the control member 82, the circuits to the motor 138 cannot become energized. When the pattern cam shaft has completed its rotation, the block 74 on the gear 159 engages the end of an arm 250 (see Fig. 6) secured to the shaft 78 which forms the fulcrum for the lever 76. To the upper end of the shaft 78 is fixed an arm 252 connected to one arm of the bell crank lever 240 by a link 254. The arm of the lever 240 connected to the link 254 is so bent that the pivot 256 for joining the link and the arm lies substantially concentric with the pivot 46 of the feed control arm. Rocking the arm 250 on the shaft 78 causes the lever 240 to shift the shaft 226 lengthwise. The worm 224 at the forward end of the shaft presses against the bearing block 228 and causes the arm 232 to move about the stud screw 234 (Fig. 8). The hub of the arm 232 is surrounded by the hub of a locking arm 258 provided with a detent 260 which engages a notch 260 in the lever 88 whenever the shaft 226 is moved lengthwise by engagement of the block 74 with the arm 250. To prevent breakage, in case the detent of the arm 258 does not engage the notch 260, a coiled spring 262 is compressed between the ends of passages formed in the arm 232 and the arm 258, respectively. The spring 262 is normally held under compression by a projection 264 which engages the side of the lever 258.

To short circuit the stationary control contacts 134 and 136 at the end of a seam, the lower ends of the contacts extending downwardly through insulating bushings 265 carried by the feed control arm 42 are bridged by a switch member 266 pivotally mounted on a bell-crank lever 267. The lever 267 is fulcrumed on a bolt 268 supported by the feed arm. Switch member 266 is operated simultaneously with the locking arm 258 by a link 269 pivotally connected to a downwardly extending arm of lever 267 and a lug 270 (see Fig. 10) extending from the bearing block 228.

Locking arm 258 is disengaged from lever 88 and switch member 266 from contacts 134 and 136 by reverse movement of shaft 226, the bearing block 228 and shaft being held against relative movement by a screw 271. The bearing 238 at the other end of the shaft is similarly held by a screw 272 (see Fig. 15). To reverse the movement of the shaft 226, the lever 250 is returned to

its original position after the machine is restarted by a tension spring 273 (see Figs. 4 and 6) stretched between the lever and a stationary part.

In the machine of the Haas application above referred to, means is provided to bring the machine to rest at any time during the operation of the shoe at which the thread becomes slack or broken. As more completely described in the Haas application, slack thread is detected in the present machine by completing a circuit whenever the auxiliary take-up of the machine is at the limit of its thread retracting movement while a stitch is being set. In Figure 17, the main take-up is diagrammatically indicated at 274 and the auxiliary take-up at 275. The main take-up is secured to a shaft operating a pair of segmental electrical contacts 276 against which a pair of brushes 277 may bear. The auxiliary take-up carries a spring contact 278 which engages the segmental contacts 276 to complete the circuit between them whenever slack thread occurs. This completes the connections from the ground 156 of transformer 154 through a ground 279 between brushes 277, and energizes a relay 280. The relay 280 completes the circuit between its contacts 282 energizing a tripping solenoid 284, the armature of which is connected to a hook member 286 for actuating a flipper member 288 cooperating with the stop mechanism of the machine to bring the machine to rest. When the machine is stopped, in this manner, the lever 88 is not locked by the detent of the locking member 258 so that the control member may be actuated in either direction, even though the shoe is disengaged from the sewing mechanism. The size adjustable connections between cam shaft 38 and feed control lever 42 are not unlocked when the machine is stopped by broken thread, so that if the shoe is moved manually in the line of feed either in or against the direction of feed, the control member 82 will be actuated accordingly and the motor 138 will rotate the pattern cam shaft to the proper position. The shoe may thus be presented properly to the sewing devices and the machine restarted at the end of the last properly formed stitch without further adjustment.

To provide the proper initial tension to the springs 84 which actuate the control member so that when the follower 128 engages the portion of smallest radius on the cam 124, all of the contacts actuated by the control member will be engaged, adjusting screws 290 and 292 are carried by the L-shaped levers 98 and 100, respectively. The adjusting screws 290 and 292 engage the hub of the lever 92 and hold the levers 98 and 100 at the desired positions. To limit the angular movement of the lever 92, additional set screws 294 and 296 extend through lugs carried by the control arm 42 into close proximity to a projection 298 on the lever 92. Further adjustment of the operation of the control member is afforded by regulating the set screws 94 and 96 which change the amount of rotary movement permitted to the lever 92 before actuating the L-shaped levers. The control member after proper adjustments are made is protected by a suitable cover 299 secured to the control arm 42. As a still further means of securing accurate control by the control member, the motor 138 is provided with a uniform friction load to prevent the momentum of the rotating parts from causing too great a change in the speed of the cam shaft. The friction load on the motor is effected by a

brake member 300 of ordinary construction acting directly on the motor shaft.

The nature and scope of the present invention having been indicated, and an embodiment of the several features of the invention having been specifically described, what is claimed is:

1. A shoe machine having, in combination, means for operating upon a shoe, a shoe supporting jack movable relatively to the operating means, means for imparting a feeding movement to the shoe, mechanism for changing the relative positions of the operating means and the jack to present the shoe properly to the operating means as the point of operation is transferred about the shoe by the feeding means, a control member for relatively changing the speeds of the position changing mechanism and the feeding means, connections between the position changing mechanism and the jack for actuating the control member in a manner to return the feeding means and the position-changing mechanism to the proper speeds when the feeding movement of the shoe is out of time with positioning movements imparted by the position changing mechanism, and regulating means operating with said connections for actuating the control member at recurring intervals for a length of time in each interval varying with the extent by which the feeding movement and the positioning movement are relatively out of time.

2. A shoe machine having, in combination, means for operating upon a shoe, a shoe supporting jack movable relatively to the operating means, means for imparting a feeding movement to the shoe, mechanism for changing the relative positions of the operating means and the jack to present the shoe properly to the operating means as the point of operation is transferred about the shoe by the feeding means, a control member for relatively changing the speeds of the position changing mechanism and the feeding means, connections between the position changing mechanism and the jack for actuating the control member in a manner to return the feeding means and the position changing mechanism to the proper speeds when the feeding movement of the shoe is out of time with positioning movements imparted by the position changing mechanism, regulating means cooperating with said connections for actuating the control member for a variable length of time, and driving means for the regulating means for causing the regulating means to hold the control member in actuated and inactive positions alternately during recurring intervals, in each of which the time actuated bears a relationship to the time held inactive corresponding to the extent by which the feeding movement and the positioning movement are relatively out of time.

3. A shoe machine having, in combination, means for operating upon a shoe, a shoe supporting jack movable relatively to the operating means, means for imparting a feeding movement to the shoe, mechanism for changing the relative positions of the operating means and the jack to present the shoe properly to the operating means as the point of operation is transferred about the shoe by the feeding means, a control member for relatively changing the speeds of the position changing mechanism and the feeding means, connections between the position changing mechanism and the jack for exerting a force on said member when the feeding movement of the shoe does not relatively correspond with positioning movements imparted by the position

changing mechanism, and regulating means co-operating with said connections for actuating the control member at recurring intervals for a length of time varying with the intensity of said force 5 during each interval.

4. A shoe machine having in combination, means for operating upon a shoe, a shoe supporting jack movable relatively to the operating means, means for feeding the shoe, mechanism 10 for changing the relative positions of the operating means and the jack to present the shoe properly to the operating means as the point of operation is transferred about the shoe by the feeding means, a control member for relatively 15 changing the speeds of the position changing mechanism and the feeding means, connections between the position changing mechanism and the jack actuated by displacement of the feeding position of the shoe from the corresponding 20 proper relative positions of the jack and the operating means to exert a force on said member, and regulating means cooperating with said connections for subjecting the control member to another force to actuate it during successive 25 periods of time and at a time in each period varying with the feeding displacement during that period.

5. A shoe machine having, in combination, means for operating upon a shoe, a shoe supporting jack movable relatively to the operating 30 means, means for feeding the shoe, mechanism for changing the relative positions of the operating means and the jack to present the shoe properly to the operating means as the point of operation is transferred about the shoe by the 35 feeding means, a control member for relatively changing the speeds of the position changing mechanism and the feeding means, connections between the position changing mechanism and the jack actuated by displacement of the feeding 40 position of the shoe from the corresponding proper relative position of the jack and the operating means to exert a force on said member, regulating means cooperating with said connections for subjecting the control member to another 45 force to actuate it during successive periods of time, and driving means for the regulating means for causing the time in each period in which the control member is held inactive to bear a relationship to each actuated time corresponding to 50 the ratio of the respective forces during that period.

6. A shoe machine having, in combination, means for operating upon a shoe, a shoe supporting jack movable relatively to the operating 55 means, means for imparting a feeding movement to the shoe, mechanism for changing the relative position of the operating means and the jack to present the shoe properly to the operating means as the point of operation is transferred about the shoe by the feeding means, a control member for relatively changing the speeds of the position 60 changing mechanism and the feeding means, connections between the position changing mechanism and the jack including a spring for exerting a force on said member when the feeding movement of the shoe does not correspond with positioning movements imparted by the position changing mechanism, and regulating means having a second spring connected to said control member for opposing the force of the first mentioned spring to resist actuation of the control member during each of a series of recurring 65 intervals and to prevent actuation of the control member for a length of time during each interval 70

varying with the force intensity of said first spring.

7. A shoe machine having, in combination, means for operating upon a shoe, means for feeding the shoe, a shoe supporting jack movable 5 relatively to the operating means, a rotating pattern cam shaft, mechanism operated by the cam shaft for changing the relative positions of the shoe and the operating means to present the shoe properly to the operating means as the point of 10 operation is transferred about the shoe by the feeding means, a control member for relatively changing the speeds of the feeding means and cam shaft, and means for actuating said control member during recurring periods of equal time 15 when the pattern cam shaft is displaced from the proper rotary position relative to the feeding position of the shoe, to cause a correcting impulse to be imparted to said cam shaft corresponding to the extent of displacement during each period. 20

8. A shoe machine having, in combination, means for operating upon a shoe, a shoe supporting jack movable relatively to the operating means, means for imparting a feeding movement to the shoe, a rotating pattern cam shaft for 25 changing the relative positions of the operating means and the jack to present the shoe properly to the operating means as the point of operation is transferred about the shoe by the feeding means, a control member for relatively changing 30 the speeds of the feeding means and cam shaft, and means for actuating the control member to impart periodic correctional impulses to said cam shaft varying in duration with the extent to which the feeding movement of the shoe and the 35 rotation of the cam shaft are relatively out of time.

9. A shoe machine having, in combination, means for operating upon a shoe, a shoe supporting jack movable relatively to the operating 40 means, means for imparting a feeding movement to the shoe, a rotating pattern cam shaft, mechanism actuated by the cam shaft for changing the relative positions of the operating means and the jack to present the shoe properly to the operating means as the point of operation is transferred about the shoe by the feeding means, a control member for imparting correctional impulses to said driving means, and regulating 45 means cooperating with the control member for causing said impulses to occur alternately with intervals of inactivity which bear a relationship to the duration of the respective impulse corresponding to the extent by which the feeding movement of the shoe and the rotation of the cam shaft are relatively out of time. 50

10. A shoe machine having, in combination, means for operating upon a shoe, means for feeding the shoe, a shoe supporting jack movable 60 relatively to the operating means, a rotary pattern cam shaft, mechanism operated by the cam shaft for changing the relative positions of the jack and the operating means to present the shoe properly to the operating means as the point of operation is transferred about the shoe by the feeding means, a rotary regulating cam having a portion of gradually changing radius, a control member actuated jointly by the pattern cam shaft and the timing cam to impart correctional 65 impulses to the cam shaft when the feeding movement of the shoe is out of time with the positioning movements imparted by the position changing mechanism, and a driving shaft for actuating the timing cam with sufficient rapidity to prevent the 70 75

correctional impulses from disturbing proper operation of the operating means on the shoe.

11. A shoe machine having, in combination, means for operating upon a shoe, a shoe supporting jack movable relatively to the operating means, means for imparting a feeding movement to the shoe, means for changing the rate of shoe feeding movement, mechanism for changing the relative positions of the operating means and the jack to present the shoe properly to the operating means as the point of operation is transferred about the shoe by the feeding means, a control member for relatively changing the speeds of the position changing mechanism and the feeding means, connections between the jack and the position changing mechanism for exerting a force on said member when the feeding movement of the shoe is out of time with positioning movements imparted by the position changing mechanism, regulating means cooperating with said connections for actuating the control member at recurring intervals for a length of time varying with the extent by which the feeding movement and the positioning movements are out of time, and driving means for actuating the regulating means with sufficient rapidity to reduce each relative speed change between the position changing mechanism and the feeding means to an amount which will not disturb proper operation of the operating means for any adjustment of the feeding means.

12. A shoe machine having, in combination, means for operating upon a shoe, a shoe supporting jack movable relatively to the operating means, means for imparting a feeding movement to the shoe, means for changing the rate of shoe feeding movement, mechanism for changing the relative positions of the operating means and the jack to present the shoe properly to the operating means as the point of operation is transferred about the shoe by the feeding means, a control member for relatively changing the speeds of the position changing mechanism and the feeding means, connections adjustable to correspond with different sizes of shoes between the jack and the position changing mechanism for exerting a force on said member when the feeding movement of the shoe is out of time with positioning movements imparted by the position changing mechanism, regulating means cooperating with said connections for actuating the control member at recurring intervals for a length of time varying with the extent by which the feeding movement and the positioning movement are out of time, and driving means for actuating the regulating means with sufficient rapidity to reduce each relative speed change between the position changing mechanism and the feeding means to an amount which will not disturb proper operation of the operating means for any adjustment of the feeding means and any size of shoe.

13. A shoe machine having, in combination, a main driver for the machine, means for operating upon a shoe, means for feeding the shoe, a shoe supporting jack movable relatively to the operating means, a pattern cam shaft, mechanism operated by the cam shaft for changing the relative positions of the operating means and the jack to present the shoe properly to the operating means as the point of operation is transferred about the shoe by the feeding means, means separate from the main driver for relatively changing the positions of the shoe in the line of feed and of the cam shaft, a control member for said separate means, connections between the jack and the cam

shaft, certain parts of which are arranged for limited relative movement to actuate the control member when the feeding position of the shoe is displaced from the corresponding proper relative positions of the jack and the operating means, and means for preventing relative change in position of the shoe in the line of feed and of the cam shaft when the machine is brought to rest.

14. A shoe machine having, in combination, means for operating upon a shoe, means for feeding the shoe, a shoe supporting jack movable relatively to the operating means, a pattern cam shaft, mechanism operated by the cam shaft for changing the relative positions of the operating means and the jack to present the shoe properly to the operating means as the point of operation is transferred about the shoe by the feeding means, a control member for relatively changing the speeds of the feeding means and the cam shaft, connections adjustable for different sizes of shoes between the jack and the cam shaft including parts arranged for limited relative movement to actuate the control member when the feeding position of the shoe is displaced from the corresponding proper relative positions of the jack and the operating means, devices for locking the adjustment of said connections during operation of the machine, and means for locking said parts of the connections against relative movement to prevent actuation of the control member when the machine is brought to rest.

15. A shoe machine having, in combination, means for operating upon a shoe, means for feeding the shoe, a shoe supporting jack movable relatively to the operating means, a pattern cam shaft, mechanism operated by the cam shaft for changing the relative positions of the operating means and the jack to present the shoe properly to the operating means as the point of operation is transferred about the shoe by the feeding means, a control member for relatively changing the speeds of the feeding means and the cam shaft, connections between the jack and the cam shaft including parts arranged for limited relative movement to actuate the control member when the feeding position of the shoe is displaced from the corresponding proper relative positions of the jack and the operating means, motion adjustable linkage actuated in moving the shoe on the jack to starting position in the machine for changing in accordance with the size of a shoe the operation of the connections, devices for locking said adjustable linkage during operation of the machine, and means for locking said parts of the control actuating connection against relative movement to prevent misadjustment of the motion adjusting linkage when the locking devices therefor are unlocked.

16. In a system for regulating the movements of two actuated parts, a control member for relatively changing the speeds of the parts, connections actuated by displacement of the parts from predetermined relative positions for exerting a force on said member corresponding in intensity to the extent of displacement, and regulating means cooperating with said connections for causing said force to actuate the control member periodically and for a length of time in each period varying with the extent of said displacement.

17. In a system for regulating the movements of two actuated parts, a control member for relatively changing the speeds of said parts, con-

nections actuated by displacement of the parts from predetermined relative positions for exerting a force on said member corresponding in intensity to the extent of displacement, and regulating means for exerting a periodically varying force on said member opposing the force exerted by said connections for a time during each period varying with variations in the force of said connections.

18. In a system for regulating the movements of two actuated parts, a control member for relatively changing the speeds of said parts, a regulating spring connected to said member tending to hold the member in inactive position, an actuating spring connected to said member tending to overcome the force of the regulating spring, connections for stressing the actuating spring whenever the parts are displaced from predetermined relative positions, and vibrating means for periodically stressing the regulating spring to cause said control member to be held in actuated position for a length of time in each period varying with the extent by which the parts are relatively displaced.

19. In a system for regulating the movements of two actuated parts, a control member for relatively changing the speeds of said parts, a regulating spring connected to said member tending to hold the member in inactive position, an actuating spring connected to said member tending to overcome the force of the regulating spring, connections for stressing the actuating spring whenever the parts are displaced from predetermined relative positions, a lever connected to the regulating spring, and a continuously rotating cam for actuating the lever periodically to cause the control member to be held alternately in inactive and in actuated positions the relative times of which bear a relationship corresponding to the extent by which the parts are relatively displaced.

20. In a system for regulating the movements of two actuated parts, a control member for relatively changing the speeds of the parts, electrical contacts operated by the control member, mechanism for increasing the speed of one part relatively to that of the other when a circuit is completed through one only of the contacts and for decreasing the speed of said one part relatively to that of the other when a circuit is completed through the other only of said contacts, a regulating spring connected to said member in a position to prevent increasing or decreasing the speed of said parts, actuating springs arranged when stressed to overcome the force of the regulating spring and change the position of the control member, connections between the parts for stressing one of the springs when the parts are displaced from predetermined relative positions, and vibrating means for periodically stressing the regulating spring to cause a circuit to be completed through one only of the contacts for a length of time in each period varying with the extent by which the parts are relatively displaced.

21. In a system for regulating the movements of two actuated parts, a control lever, a fulcrum for said lever, electrical contacts actuated by angular movement of the control lever in either direction about the fulcrum, mechanism for increasing the speed of one part relatively to that of the other when a circuit is completed through one only of the contacts and for decreasing the speed of said one part relatively to that of the other when a circuit is completed through an-

other only of said contacts, a regulating spring connected to the fulcrum of the control lever tending to prevent actuation of the contacts, actuating springs connected to the control lever at either side of the fulcrum and arranged to overcome the force of the regulating spring, connections between the parts for stressing one of the actuating springs when the parts are displaced from predetermined relative positions to impart angular movement to the control lever, and vibrating means for periodically stressing the regulating spring to cause a circuit to be completed through one only of the contacts for a length of time in each period varying with the extent by which the parts are relatively displaced.

22. In a system for regulating the movements of two actuated parts, a control lever, a fulcrum for said lever, stationary electrical contacts, movable contacts actuated by the control lever, mechanism for increasing the speed of one part relatively to that of the other when one of the movable contacts is disengaged from a corresponding stationary contact and for decreasing the speed of said one part relatively to that of the other when the other of said contacts is disengaged from a corresponding stationary contact, a regulating spring connected to the fulcrum of the control lever tending to bring both movable contacts into engagement with their respective stationary contacts, actuating springs connected to the control lever at either side of the fulcrum and arranged to overcome the force of the regulating spring, connections between the parts for stressing one of the actuating springs when the parts are displaced from predetermined relative positions to disengage one of the movable contacts from a stationary contact, and vibrating means for periodically stressing the regulating spring to cause said disengaged contact to remain disengaged from the corresponding stationary contact for a length of time in each period varying with the extent by which the parts are relatively displaced.

23. A shoe machine having, in combination, means for operating upon a shoe, a shoe supporting jack movable relatively to the operating means, means for feeding relatively the shoe and the operating means to transfer the point of operation along the shoe, mechanism for changing the relative positions of the operating means and the jack to present the shoe properly to the operating means as the point of operation is transferred along the shoe by the feeding means, a driver for the operating and feeding means, driving means separate from the operating means driver for actuating the position changing mechanism, and a control member actuated by displacement of the position changing mechanism from predetermined relation with the feeding position of the shoe for changing the speed of the separate driving means relatively to the speed of the driver for the operating means.

24. A shoe machine having, in combination, means for operating upon a shoe, a shoe supporting jack movable relatively to the operating means, means for feeding relatively the shoe and the operating means to transfer the point of operation along the shoe, mechanism for changing the relative positions of the operating means and the jack to present the shoe properly to the operating means as the point of operation is transferred along the shoe by the feeding means, a driver for the operating and feeding means, an electric motor separate from the operating means driver for actuating the position changing

mechanism, and control contacts for said motor actuated by displacement of the position changing mechanism from predetermined relation with the feeding position of the shoe for changing the speed of the separate electric motor relatively to the speed of the driver for the operating and feeding means.

- 5 25. A shoe machine having, in combination, means for operating upon a shoe, a shoe supporting jack movable relatively to the operating means, means for feeding relatively the shoe and the operating means to transfer the point of operation along the shoe, a pattern cam shaft, mechanism operated by the cam shaft for changing the relative positions of the operating means and the jack to present the shoe properly to the operating means as the point of operation is transferred along the shoe by the feeding means, a driver for the operating and feeding means, a 10 driving gear train including a set of differential gears connecting the operating means and the cam shaft, an electric motor separate from the operating means driver connected to the differential gears to rotate the cam shaft at a different speed than that at which it is rotated by the gear train, and control contacts for said motor actuated by displacement of the feeding position of the shoe with relation to the position of the cam shaft.
- 15 26. A shoe machine having, in combination, means for operating upon a shoe, a shoe supporting jack movable relatively to the operating means, means for feeding relatively the shoe and the operating means to transfer the point of operation along the shoe, a pattern cam shaft, mechanism operated by the cam shaft for changing the relative positions of the operating means and the jack to present the shoe properly to the operating means as the point of operation is transferred along the shoe by the feeding means, a driver for the operating and feeding means, a 20 driving gear train including a set of differential

gears connecting the operating means and the cam shaft, an electric motor separate from the operating means driver connected to the differential gears to rotate the cam shaft at a different speed than that by which it is rotated by the gear train, and control contacts for said motor actuated by displacement of the feeding position of the shoe with relation to the position of the cam shaft to cause the motor to be rotated in either forward or reverse directions.

27. A shoe machine having, in combination, means for operating upon a shoe, a shoe supporting jack movable relatively to the operating means, means for imparting a feeding movement to the shoe, mechanism for changing the relative positions of the operating means and the jack to present the shoe properly to the operating means as the point of operation is transferred about the shoe by the feeding means, a control member for relatively changing the speeds of the position changing mechanism and the feeding means, connections between the position changing mechanism and the jack for actuating the control member in a manner to return the feeding means and the position changing mechanism to the proper speeds when the feeding movement of the shoe is out of time with positioning movements imparted by the position changing mechanism, regulating means cooperating with said connections for actuating the control member at recurring intervals for a length of time varying with the extent by which the feeding movement and the positioning movement are relatively out of time, and driving means for causing the regulating means to actuate the control member at such a rate of speed that the time during which the control member is actuated in each interval cannot produce such a change of speed between the feeding and positioning movements as to interfere with the operation of the operating means.

LAURENCE E. TOPHAM.
